UNITED STATES PATENT OFFICE

2,497,620

THREE-WAY LOCK FOR TOY IRONING
BOARDS

Ernest Melberg, Norway, Iowa

Application September 6, 1945, Serial No. 614,713

4 Claims. (Cl. 38—123)

1

This invention relates to an ironing board of full or toy size.

The object of the invention is the provision of means holding one leg that may be placed in two different positions corresponding to three different heights of the board proper above the floor or other supporting surface. These means also function as a lock locking the legs of the board in folded or collapsed position upon the bottom side of the board proper so that the entire structure may be handled or stored away in a narrow space without the legs spreading and hampering the user.

The invention consists in the details of construction whereby certain important advantages are attained and which will be described.

The novel features of my invention will herein-after be particularly claimed.

The description is illustrated by the accompanying drawings in which:

Figure 1 is a bottom plan view of the ironing board with the legs in position collapsed against the bottom of the board;

Figure 2 is a longitudinal central section on line 2—2 of Figure 1;

Figure 3 is a central longitudinal section through the board with the legs extended the lowermost ends of which are omitted and the latch set in a position giving the board the maximum height above the floor;

Figure 4 is a section similar to that of Figure 3 with the distinction however that the latch holds the legs in a position in which the height of the board above the floor is less than that of the preceding figure;

Figure 5 is a detail sectional view of the pivot means attached to the bottom of the board and to which one pair of the legs are pivoted;

Figure 6 is a transverse section on line 6—6 of Figure 4;

Figure 7 is a longitudinal detail section on line 7—7 of Figure 6 through the latch set in the position of Figure 4.

Similar reference characters are employed to designate similar parts throughout the figures.

The board proper B of moderate thickness is generally oblong and has its longitudinal edges approaching one another towards the right hand end. Beneath the board and near the left hand right-angled end of the same are blocks 2 secured to the board by nails 3 or other fastening means. These blocks have aligned apertures 4 through which extends a rod 5 having ends protruding beyond the blocks and passing through apertures 6 in the upper portions of downwardly

2

diverging legs 7 which are connected at an intermediate point by a rod 8 and near their bottom ends by a rod 9.

To the bottom of the board a latch 10 is pivoted by a screw nail or other fastening means 11. The latch is provided with a notch 12 extending parallel to the plane of the board and formed in the end remote from pivot 11. Another notch 13 is formed in the bottom surface of the latch, between the pivot 11 and notch 12.

Upon rod 8 is pivoted another shorter pair of legs 14 the upper converging ends of which carry a rod 15 while the lower diverging ends carry the rod 16. Owing to the fact that the leg structure 14 is shorter than leg structure 7 and passes through the latter, the former may be folded into the latter in which position the latch 10 may be turned to the position of Figure 1 in which the rod 8 is lodged in the notch 12 and the entire board is locked together. If it is desired to use the board, the latch 10 is turned to the position of Figure 4, the board is inverted, the legs are unfolded to a crossed position in which the rod 15 can be lodged in notch 13. If the user finds the board inconveniently low, he may adjust the same to a higher elevation by lifting the board so as to disengage rod 15 from the notch 13, then turning the latch to a reverse position of Figure 3 in which he may rest such rod in the same notch now located on the opposite side of the pivot or in the end notch 12, if a still greater height of the board above the floor surface is desired.

Having described the invention what I claim and try to secure by Letters Patent is:

1. In combination with an ironing board provided with a stand on the underside thereof composed of crossed hinged legs foldable into one another and one of which legs is pivotally connected at its upper end to the underside of the board, a block rotatably connected to the underside of the board and provided with a notch in one end thereof and a second notch in its underside and between said end and the point of connection of the block to the board, said first notch being engageable with the hinge of the legs for locking the stand in a collapsed position against the board when the block is disposed with said first notch facing toward the pivot of said leg to the board, a rod extending transversely from the upper end of the other leg, and said first notch being engageable, in the same position of the block with the rod for holding the stand in one extended position, said second notch being engageable with the rod in said aforementioned position and in a second position of the block

in which said first notch is disposed to face in the opposite direction for supporting the stand in two other extended positions relatively to the ironing board.

2. A supporting structure comprising an ironing board, a pair of legs pivotally mounted at one end thereof on the underside of the ironing board, a second pair of legs pivotally connected intermediate of their ends to an intermediate portion of the first pair of legs and in crossed relationship, a rung connecting corresponding ends of the second pair of legs, and a block rotatably connected to the underside of the ironing board in spaced relationship to the pivotal mounting of said first pair of legs, said block having a downwardly opening notch for receiving the rung to retain the pairs of legs in extended positions, and said block being rotatable for displacing said notch toward or away from the pivot of the first pair of legs to the ironing board for varying the extended positions of the pairs of legs when the rung is in engagement with the notch, said block having a notch in one end thereof to selectively receive the rung, when the block is disposed with said last mentioned notch facing toward the pivotal mounting of the first pair of legs on the ironing board, for supporting the legs in another extended position.

3. A supporting structure comprising an ironing board, a pair of legs pivotally mounted at one end thereof on the underside of the ironing board, a second pair of legs pivotally connected intermediate of their ends to an intermediate portion of the first pair of legs and in crossed relationship, a rung connecting corresponding ends of the second pair of legs, and a block rotatably connected to the underside of the ironing board in spaced relationship to the pivotal mounting of said first pair of legs, said block having a downwardly opening notch for receiving the rung to retain the pairs of legs in extended positions, and said block being rotatable for displacing said notch toward or away from the pivot of the first pair of legs to the ironing board for varying the extended positions of the pairs of legs when the rung is in engagement with the notch, said block having a notch in one end thereof to selectively receive the rung, when the block is disposed with said last mentioned notch facing toward the pivotal mounting of the first pair of legs on the iron-

ing board, for supporting the legs in another extended position, and a pivot pin forming the pivotal connection of the second pair of legs to the first mentioned pair of legs, said last mentioned notch being disposed to engage the pivot pin in its aforementioned position to retain the legs in a folded or collapsed position against the underside of the ironing board.

4. A supporting structure comprising an ironing board, a pair of legs pivotally mounted at one end thereof on the underside of the ironing board, a second pair of legs pivotally connected intermediate of their ends to an intermediate portion of the first pair of legs and in crossed relationship, a rung connecting corresponding ends of the second pair of legs, and a block rotatably connected to the underside of the ironing board in spaced relationship to the pivotal mounting of said first pair of legs, said block having a downwardly opening notch for receiving the rung to retain the pairs of legs in extended positions, and said block being rotatable for displacing said notch toward or away from the pivot of the first pair of legs to the ironing board for varying the extended positions of the pairs of legs when the rung is in engagement with the notch, a pivot pin forming the pivotal connection of the second pair of legs to the first mentioned pair of legs, and said block being provided with a notch at one end thereof for engaging said pivot pin when the pairs of legs are folded or collapsed against the ironing board and when the block is disposed with said last mentioned notch facing toward the pivotal mounting of the first mentioned pair of legs to the ironing board, for retaining the pairs of legs in a folded or collapsed position.
